UNITED STATES PATENT OFFICE

JOHN ATKINSON HUNT, OF BOSTON, MASSACHUSETTS, ASSIGNOR TO HUNT HYDRO BURNER COMPANY, OF WORCESTER, MASSACHUSETTS, A CORPORATION

BURNER

Refiled for abandoned application Serial No. 172,900, filed March 4, 1927. This application filed September 13, 1929. Serial No. 392,297.

This invention relates to a burner for liquid fuel, the present invention being an improvement over that forming the subject matter of a patent granted to me on December 7, 1909, No. 942,857, the general object of the invention being to provide a casing for enclosing the burner parts for increasing the efficiency of the same so that a less number of tubes can be used in the construction of the burner.

10 A further object of the invention is to provide means whereby the tubes can be welded to their headers so as to eliminate the threading of the tubes and headers.

This invention also consists in certain other 15 features of construction and in the combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:—

25 Figure 1 is an elevation of the complete device.

Figure 2 is a plan view thereof.

Figure 3 is a section on line 3—3 of Figure 1.

30 Figure 4 is a section on line 4—4 of Figure 2.

Figure 5 is a section on line 5—5 of Figure 4.

Figure 6 is a sectional detail view showing 35 a tube welded to its header.

As shown in these views, the burner forming the subject matter of the before mentioned patent comprises a mixing tube 1 which has its ends connected with the headers 2 and 3, 40 the burner tubes 4 which are connected with the header 3 and the two sets of tubes and headers 5 and 6 which are connected with the header 2, with the means indicated generally at 7 and 8 for introducing liquid fuel into one

45 of the sets of tubes and water into the other set so that these liquids will be vaporized as they pass through the tubes and the two vapors mixed together in the mixing tube so that they will produce a combustible mixture

50 which will escape through the slots of the

burner tubes 4. Instead of threading the ends of the tubes into their headers, as illustrated in the before mentioned patent, I taper each end of each tube, as shown at 9 in Figure 6, and make the opening in the header for receiving said end of flaring shape, as shown at 10 in said Figure 6, and then the parts are welded together, as shown at 11. This will eliminate the threading of the tubes and headers and will enable the burner parts to be 55 more easily assembled.

I also provide a casing 12 for receiving the burner, this casing having a perforated hinged cover 13 which is held in closed position by the latch 14. It is also provided with the strengthening webs 15 on its interior side walls and the bottom of the casing is provided with the holes 16 for admitting air into the casing, any oil collecting on the bottom of the casing being prevented from escaping 60 through said holes by the ribs 17 formed on the bottom around the holes. An opening 18 is formed in one side of the casing adjacent its bottom so that the oil on the bottom of the casing can be ignited to start the burner, this 65 oil escaping through the hole 19 formed in one or both of the burner tubes. This casing will retain the heat close to the burner so that the liquids in the tubes will more quickly vaporize and said casing takes the place of the pan used in the before mentioned patent. By the use of this casing, some of the vaporizing tubes can be omitted, thus cheapening the 70 cost of the burner. The flames from the burning mixture, escape through the perforated 75 top or cover and heat the stove or other device with which the burner is used. By having the cover hinged to the casing, access can be readily had to the burner parts for cleaning or repairing the same.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

In combination with a burner for vaporiz-

ing liquid fuel and water and burning the resulting vapors, a casing in which the burner is placed, a perforated cover for the casing, the bottom of the casing having perforations 5 therein for admitting air to the casing, upright ribs surrounding the perforations so that fuel from the burner can collect in the bottom of the casing, said casing having openings therein for permitting ignition of the fuel 10 on the bottom thereof to start the burner and laterally extending strengthening webs connected with the interior walls and bottom of the casing.

15 In testimony whereof I affix my signature.
JOHN ATKINSON HUNT.
